United States Patent Office

Des. 224,993
Patented Oct. 31, 1972

224,993

PILLOW OR SIMILAR ARTICLE

Linda Ellen Levine, 7530 Stonecrest, and Deborah Ann Zippel, 4407 Mill Run, both of Dallas, Tex. 75222

Filed Mar. 17, 1971, Ser. No. 125,467

Term of patent 14 years

Int. Cl. D6—09

U.S. Cl. D3—9

Fig. 1

Fig. 3

Fig. 2

Fig. 4

FIG. 1 is a top plan view of a pillow or similar article, showing my new design;

FIG. 2 is a front elevational view thereof;

FIG. 3 is a perspective view thereof; and

FIG. 4 is a side elevational view.

I claim:

The ornamental design for a pillow or similar article, substantially as shown and described.
